Thos. H. White.

Inventor

William Wyatt

United States Patent Office.

WILLIAM WYATT, OF NEW BEDFORD, MASSACHUSETTS.

Letters Patent No. 65,852, dated June 18, 1867.

IMPROVED MODE FOR FURLING AND REEFING SAILS.

The Schedule referred to in these Letters Patent and making part of the same.

TO ALL WHOM IT MAY CONCERN:

Be it known that I, WILLIAM WYATT, of New Bedford, in the county of Bristol, in the State of Massachusetts, have invented a new and improved Mode of Furling and Reefing "Top-Gallant" Sails and "Royals"; and I do hereby declare that the following is a full and exact description thereof, reference being had to the accompanying drawings, and to the letters of reference marked thereon.

My invention consists in a mode by which "top-gallant" sails and "royals" may be furled and reefed, by means of "luff-lines" and "head-lines" and travellers, as herein set forth, without ascending from the deck to the yard for said purposes.

Figure 1 is a view of a mast, of the yards, and a sail spread, with "head-lines," &c.

Figure 2 is a view with the yard lowered and supported by the lifts, showing the head of the sail drawn in.

Figure 3 is a view with the yard let down, and the leaches clewed up.

Figure 4 is transverse section of the yards, showing the grooved way.

Figure 5 is a traveller.

Fig. 1. A' is the mast; B', the sail; C C', the yards, which need no further description; D¹ D¹, the "luff-lines;" E' E', the "head-lines," (the course of which, behind the sail, may be seen by the dotted lines;) G¹, blocks through which the "head-lines" run; a' a' a', &c., travellers. Fig. 2. B², the sail clewed down; D² D², the "luff-lines;" E² E², the "head-lines;" F² F², &c., plates secured to the yard, forming grooved ways, in which the travellers run; G² G² are blocks through which the "head-lines" run. Fig. 3. B³, the sail drawn in and clewed up; D³ D³, "luff-lines;" E³ E³, "head-lines;" e³ shows the course of one of the "head-lines" towards the deck, where both are secured; F³ F³, metallic plates forming the grooved ways. Fig. 4. F⁴ F⁴ are plates shown by F³ F³, in fig. 3; H⁴ is a groove cut in the yard, to allow a free passage for the travellers. Fig. 5 is a view of a traveller.

Operation.

The several parts of my invention being constructed and affixed as herein set forth, the "head-lines," "luff-lines," and "leashes" rove and adjusted, as also shown, the operation may be noted. Yard C' (see fig. 1) is raised in the usual manner, the "head-lines" E' E' being secured to the corners of the sail at Y' Y'. The upper edge of the sail being affixed to the travellers a' a' a', &c., is hauled out, the travellers running in the grooved ways as the yard is raised, the "head-lines" running through blocks G¹ G¹, on the ends of the yard, the quarter-blocks on the under side of the yard, and made fast. By lowering the yard, the "luff-lines" D¹ D¹ being also affixed to the sail at Y' Y', passing through blocks on the upper side of the yard, and secured to the mast, hauls in the sail, giving it the appearance shown by fig. 2. By liberating the "sheets" d' d', clewing up, gives it the appearance of fig. 3.

I do not claim securing the "luff" and "head-lines" to the mast: they may be brought down and secured to the deck; nor do I claim the form of the slides forming the grooved ways: the way may be made in any practical manner; neither do I claim any device previously invented or patented for furling and reefing sails; but what I claim as my invention, and desire to secure by Letters Patent, is—

The combination and arrangement of the furling and reefing "top-gallant" sails and "royals," by means of "head-lines" and "luff-lines," running through blocks on the upper and under sides and ends of the yard, and travellers, affixed to the sail and running in grooved ways, formed by securing metallic plates to the yard, as herein described, operated by raising and lowering the yard, as set forth, for the purpose specified.

Witnesses:

GEO. A. TABER,

TH. E. M. WHITE.

WILLIAM WYATT.
